UNITED STATES PATENT OFFICE.

ARTHUR CRUTCHLEY, OF BROOKLYN, NEW YORK

CARRIAGE-SPRING CONNECTION.

Specification of Letters Patent.

Patented Feb. 8, 1916.

1,171,386.

Application filed December 21, 1914. Serial No. 878,355.

To all whom it may concern:

Be it known that I, ARTHUR CRUTCHLEY, a citizen of the United States, residing at the city of Brooklyn, county of Kings, and State of New York, have invented a certain new and useful Improvement in Carriage-Spring Connections, of which the following is a full, clear, and exact description, such as will enable others skilled in the art to which it appertains to make and use the same, reference being had to the accompanying drawings, forming part of this specification, in which—

My invention relates to writing machines, and specifically to the carriage moving its stationary mounting.

My invention has for its principal object the provision of an automatically releasable connection between the carriage spring and its stationary mounting.

For the purpose of disclosure, I have illustrated in the accompanying drawings two forms.

Figure 1 represents a front view of the carriage spring drum of a writing machine.

Fig. 2 represents a rear view thereof illustrating one form of my invention. Fig. 3 is a view similar to Fig. 2 showing the parts in a different position. Fig. 4 is a sectional view illustrating a modified form. Fig. 5 is a detail illustrating in perspective a portion of the modified form.

It has been observed in the operation of writing machines having a longitudinally movable carriage, and particularly in machines wherein the return movement of the carriage is automatically effected, that the flexible connection, usually in the form of a cord or band, which connects the spring drum with the carriage is subject to breakage. When this occurs, the spring drum being left free from the restraining weight of the carriage, immediately yields to the tendency of the spring, and rotating rapidly while the spring is unwinding, gains sufficient momentum to break the spring or its connections either to the drum or to the spindle to which the inner end of the spring is connected.

By my present invention, I obviate the possibility of such breakage of the spring, by providing an automatically engageable and disengageable connection between the inner end of the spring and the spindle to which it is connected.

By reference to the accompanying draw-

ings, it will be understood that 1 represents any suitable portion of the machine upon which the spring drum 2 is mounted by means of the spindle 4, which usually is independently rotatable so that the spring may be wound up initially to provide the proper tension for feeding the carriage leftwardly in the letter-space operation.

5 is the spring, one end of which 5^a is connected to the drum, and the inner end of which 5^b is adapted to be connected to the spindle 4 by the means now to be described.

6 is the flexible cord or band which is connected and partially wound upon the drum 2, the other end thereof being connected to the carriage of the machine so as to draw the same leftwardly under the influence of the spring 5. The means of connection which is provided between the inner end 5^b of the spring and the spindle 4, comprises the catch lug 7 having a forwardly presented nose, and the notched ring 8. As illustrated in Figs. 2 and 3, this notched ring is of eccentric form, and encircles the spindle 4. It is provided with the notch 8^a, in front of which in a clockwise direction the ring is formed with the inwardly extending lip 8^b. Behind the notch 8^a the ring is spiraled out so as to approach the notch 8^a gradually. The inner perimeter of the ring 8 is considerably larger than the outer perimeter of the spindle 4, the difference giving room for the travel within the ring of the lug 7. The inner end of the spring is attached to the ring 8 in such position that the tendency of the spring maintains the lip 8^b in yielding contact with the spindle 4.

When the spring is initially wound up, which is done by the rotation of the spindle 4, the lug 7 will be carried around within the ring 8, and as it approaches the notch 8^a will ride through the spiraled out portion and engage the notch with its forwardly directed nose. The lip 8^b in front of the notch, prevents the rotation of the lug 7 out of or beyond the notch. Consequently, upon further rotation of spindle 4 in a clockwise direction, as illustrated in Figs. 2 and 3, the ring 8 will be carried around therewith, and the spring 5 wound up. This will place the proper tension upon the drum 2, which tension is transmitted to the carriage through the flexible connection 6. In case of the breaking or accidental detachment of the flexible connection 6 from the carriage, the drum being left free from restraint, will

rotate in a direction clockwise as illustrated in Figs. 2 and 3 as the spring unwinds. When the tension has been released sufficiently to relieve the opposing influence of the lip 8^b against the lug 7, the ring 8 will disengage itself from the lug 7 and rotate freely in a clockwise direction, permitting the spring to unwind without rotation of the drum. Thus, it will be seen that, there being no fixed connection of the spring at its inner end, the momentum of the spring may spend itself without giving excessive momentum to the drum, and without placing any braking strain upon the spring or its connections.

In Figs. 4 and 5 is illustrated a modification. In this form the notched ring 8 has a notch cut in from one end thereof instead of from the inner perimeter thereof. The inner end of the spring is connected to the ring, and a stop pin 7^b is fixed in the spindle 4 in position such that it may be engaged in the notch. A spring 9 tends to hold the ring 8 inwardly in position where the pin 7^b will ride into the notch. Upon the release of the drum, however, the unwinding movement of the spring will cause the ring to ride off of the pin, permitting free movement of the ring independently of the spindle.

What I claim is:

1. In a writing machine, a drum mounted for rotary movement, a flexible element adapted to be wound on the drum, a spring for actuating the drum to wind the flexible element thereon, said spring having one end secured to the drum, a stationary member adapted to hold the other end of the spring against movement, and a connection between the said end of the spring and stationary member, said connection including a collar member encircling the stationary member and connected to the spring, and a lug carried by the stationary member, said lug and said collar being provided with interengaging elements whereby the connected end of the spring is held against movement in an unwinding direction but is free to move in a winding direction.
2. In a writing machine, a rotary drum, a flexible element windable upon the same,

a spring for actuating the drum to wind the flexible element thereon, said spring having one end thereof connected to the drum, a normally stationary spindle, a collar member encircling the same and attached to the other end of the spring, said spindle being provided with a lug extending radially thereof, the collar being provided with an inwardly directed lip adapted to coöperate with the spindle, said lug being adapted to engage said lip to prevent movement of the collar in an unwinding direction but to permit movement thereof in a winding direction, the inner diameter of said collar being sufficient to permit its rotation over said lug.

3. In a writing machine, a drum mounted for rotary movement, a flexible element windable upon the same, a spring for actuating the drum to wind the flexible element thereon, a normally stationary spindle, a collar encircling the spindle, said collar and said spindle being provided with coöperating means engageable upon contractive movement of the spring and disengageable upon expansive movement thereof, one end of the spring being secured to the drum and the other end thereof being secured to the collar.

4. In a machine of the class described, a revoluble member, a flexible element windable thereon, a spring for actuating the said member to wind the flexible element thereon, a normally stationary member concentrically associated with said revoluble member, an automatically releasable means for connecting the spring to the stationary member, said means comprising an abutment carried on the stationary member and an engaging portion carried on the spring and adapted to engage said abutment under winding movement of said spring and adapted to disengage itself from said abutment under unwinding influence of said spring.

In testimony whereof I hereunto affix my signature in the presence of two witnesses, this 2nd day of September, 1914.

ARTHUR CRUTCHLEY.

Witnesses:

OSCAR L. GUSTAFSON,
CHARLES A. LUNDIN.

It is hereby certified that in Letters Patent No. 1,171,386, granted February 8, 1916, upon the application of Arthur Crutchley, of Brooklyn, New York, for an improvement in "Carriage-Spring Connections," an error appears in the printed specification requiring correction as follows: Page 1, strike out line 16 and insert the words *mechanism of writing machines.*; and that the said Letters Patent should be read with this correction therein that the same may conform to the record of the case in the Patent Office.

Signed and sealed this 29th day of February, A. D., 1916.

[SEAL.]

R. F. WHITEHEAD,

Acting Commissioner of Patents.
